DESIGN FOR A SHIRT

Barnet Bratman and William Stechel, New York,
N. Y.

Application March 5, 1938, Serial No. 75,590

Term of patent 3½ years

To all whom it may concern:

Be it known that we, Barnet Bratman and William Stechel, citizens of the United States and residents of the city of New York, in the county of Kings and State of New York, whose post office addresses are, respectively, 8735 Bay Parkway, Brooklyn, New York, and 1562 Ocean Avenue, Brooklyn, New York, have invented a new, original, and ornamental Design for a Shirt, of which the following is a specification, reference being had to the accompanying drawing constituting a part thereof.

Fig. 1 is a front view of a shirt showing our new design.

Fig. 2 is the rear view thereof.

The characteristic feature of our design resides in the two rows of elastic shirring across the back of the specific blouse in association with the elastic shirring around the waist portion thereof, as shown.

We claim:

The ornamental design for a shirt substantially as shown and described.

BARNET BRATMAN.
WILLIAM STECHEL.
